INDICATING CATHODE-RAY TUBE

Henri G. Busignies, Forest Hills, N. Y., assignor
to Federal Telephone and Radio Corporation,
New York, N. Y., a corporation of Delaware

Application September 5, 1945, Serial No. 614,527

6 Claims. (Cl. 315—13)

1

This invention relates to cathode ray tubes which are used for indicating purposes.

In certain systems employing cathode ray oscilloscope tubes, such as for example direction finders and radar systems, the time base of the tube is rotated at a relatively low speed, such as for example, one turn per second to one turn every three or four seconds. While the direct light on the screen of the cathode ray tube as the beam strikes the screen is often observable in a fairly brightly illuminated room, the after-glow cannot be seen except in relatively dark rooms. This effect renders such indicators unsatisfactory in airplanes and other places where observation is made in a fairly brightly illuminated area.

An object of the present invention is the provision of an improved cathode ray tube for indicating purposes.

Another object of the present invention is the provision of a cathode ray tube in which the indication on the screen persists for a relatively long time and at a relatively greater intensity, as compared with the indication of the conventional cathode ray tube heretofore employed.

Other and further objects of the present invention will become apparent and the invention will be best understood from the following description of an embodiment thereof, reference being had to the accompanying drawings, in which:

Fig. 1 is a schematic side elevational view of a cathode ray tube embodying my invention; and

Fig. 2 is a greatly enlarged detailed view of part of the grid of the cathode ray tube of Fig. 1.

Referring now to Fig. 1, the cathode ray tube there illustrated and generally designated by the numeral 1 includes an envelope 2 having the usual type of screen 3 adapted to become illuminated when impinged upon by an electron beam. Tube 1 includes two electron guns 4 and 5 respectively, electron gun 4 emitting a narrow beam as indicated at 6, while electron gun 5 emits a cone-like beam as indicated at 7. Both electron guns 4 and 5 are directed at a grid-like electrode 8 interposed between said guns and the screen, and which is shown in greater detail in Fig. 2. Electrode or grid 8 is a foraminated structure including a plurality of openings 9 through which electrons may pass. The solid part of the electrode 8 is made up of a large number, such as for example, 10,000 to 50,000, tiny particles of conductive material, that is, metallic particles 10 which are insulated from each other, for example, by being embedded as spaced intervals in a non-conductive material 11.

2

In operation, the beam 6 from electron gun 4, which is preferably of high intensity is rotated or otherwise deflected by the deflecting means illustrated schematically and designated by the numeral 12 so that the beam 6 moves over the surface of electrode 8 and scans it in a predetermined manner. At the places on the perforated electrode 8 where the beam from electron gun 4 has a high intensity, that is at the places 10 where beam 6 impinges, the particles 10 will acquire a negative charge. This charge can be maintained for a given period, of for example a few seconds or longer and during this period the cone of electrons, that is, beam 7 emitted from electron gun 5 covers the whole area of the electrode 8. The stream of electrons passing through electrode 8, that is beam 7, is controlled by the potentials of the particles of the electrode 8 and therefore the amount of electrons from beam 7 passing through electrode 8 will be so controlled as to reproduce on the screen 3 an image which will depend upon the charges accumulated on the electrode 8 due to the action of the electron gun 4. It will therefore be seen that the image impressed upon the electrode 8 by electron gun 4 can be maintained visible on the screen as long as the charges of all the particles are maintained. The progressive discharge 20 of these particles is controlled by suitable choice of the non-conductive material 11 and the attachment of the electrode 8 to the rest of the tube structure, so that the charges dissipate at a predetermined rate.

25 It is preferred to so arrange the electron guns 4 and 5 in relation to screen 3 that while electron gun 5 is aimed toward the screen, electron gun 4 is so aimed that any of its electrons passing through electrode 8 miss the screen. For this purpose the envelope 2 may be bent as indicated at 13 and the guns 4 and 5 arranged in any suitable way, such as for example as illustrated in Fig. 1. Conventional means may be employed to collect and return the electrons emitted from 30 the electron guns.

While I have described above the principles of my invention in connection with specific apparatus, it is to be clearly understood that this description is made only by way of example and not as a limitation on the scope of my invention as defined in the accompanying claims.

I claim:

1. A cathode ray tube comprising means for producing an electron beam, a fluorescent screen 55 arranged in the path of said beam, a perforated plate of insulating material, said plate disposed

between said means and said screen, a plurality of metallic particles disposed, in random fashion, on said plate on the side thereof facing said means, and means for conditioning said electrode so as to permit the passage of electrons only through selected ones of the perforations in said plate.

2. A cathode ray tube comprising means for producing an electron beam, a fluorescent screen arranged in the path of said beam, a perforated plate of insulating material, said plate disposed between said means and said screen, a plurality of metallic particles embedded in said plate on the side thereof facing said means, said particles disposed in random fashion, and means for producing an electrostatic charge on the metallic particles on said plate adjacent selected perforations thereof to control the passage of electrons through such selected perforations.

3. A cathode ray tube according to claim 2 wherein said electron beam covers substantially the entire surface of said plate.

4. A cathode ray tube according to claim 2 wherein the means for producing a charge on said plate include means for producing a relatively narrow electron beam directed toward said plate, and means for deflecting said beam to determine the areas on said plate on which said narrow beam impinges, thereby charging the se-

lected areas so as to control the flow of electrons through the openings in said selected areas.

5. A cathode ray tube according to claim 2 wherein minute electrically conductive particles adjacent the selected perforations of said plate are adapted to be electrostatically charged to control the flow of electrons through selected perforations of said plate, said plate being adapted to dissipate the charge after a given interval.

10. 6. A cathode ray tube according to claim 2 wherein the means for producing a charge on said plate includes means for producing a relatively narrow electron beam directed toward said plate, and means for deflecting said beam to determine the areas on said plate on which said narrow beam impinges, said narrow beam being directed so that the electrons from said narrow beam passing through said plate do not impinge on said screen.
